UNITED STATES PATENT OFFICE.

RUDOLPH D'HEUREUSE, OF NEW YORK, N. Y.

DRILL FOR WOOD AND OTHER MATERIALS.

SPECIFICATION forming part of Letters Patent No. 334,757, dated January 26, 1886.

Application filed May 23, 1885. Serial No. 166,489. (No model.)

To all whom it may concern:

Be it known that I, RUDOLPH D'HEUREUSE, a citizen of the United States, and a resident of New York, in the county of New York and 5 State of New York, have invented certain new and useful Improvements in Drills for Wood and other Materials, of which the following is a specification.

My invention relates to drills for wood or 10 other materials, and it is applicable to apparatus to be operated by hand or any other motive power.

The object of my invention is to so organize 15 a drilling apparatus that it may be used for the purpose of drilling holes in places difficult or impossible of access when the ordinary drilling contrivances—such as braces, &c.—cannot be depended upon for performing the work.

20 One of the purposes for which my apparatus is especially applicable will be the drilling of holes into the window frames or casings of upper story windows, when it is desired to provide for temporary or permanent arrangement 25 for cleaning, repairing, or for the application of fire-escape apparatus.

My invention comprises a frame for supporting the drilling mechanism, which frame is provided with adjustable clamping mechanism at its foot; and this frame may be made 30 in more than one part, thus rendering it capable of being adjusted and fixed so that the drill may move in a direction parallel to the vertical axis of the clamped foot-piece, so as 35 to drill vertically, or adjusted at any desired angle with reference to the object to which the apparatus is clamped, so as to bore holes at any desired angle with relation to said object. The drilling mechanism may be mounted upon 40 this structure in a sliding frame, or the drill-spindle may be combined with any one of several well-known kinds of drill-feed devices. In either organization the construction is such 45 as to insure a progressively-forward movement of the drill of the requisite speed simultaneously with its rotating movement.

The organization of my apparatus is such 50 that it may be operated so as to bore the hole toward the operator, the drill-point moving in the direction of the operator, instead of away from him.

The subject-matter for which I desire pro-

tection in this instance is pointed out in the claims at the end of this description.

In the accompanying drawings, which form 55 a part of this description, and in which like letters indicate like parts, Figure 1 is a side elevation of one form of my apparatus; Fig. 2, a front elevation of the same; Fig. 3, a detached portion showing one form of device for 60 insuring the progressive forward movement of the drill. Fig. 4 is a front elevation of another form of the apparatus; Fig. 5, a side elevation of the same; Fig. 6, a view of one of the modes of feeding the drill that may be employed, and Fig. 7 a detail view of a part of Fig. 6.

A represents the drill-frame, with clamps B B, one of which may be permanently affixed to the stanchion d of frame A.

E is the drill-spindle, provided with the drill-chuck C and with gear G, which co-operates with the gear g, located upon the driving-spindle, which latter is provided with a crank, (or may be provided with a pulley,) O.

In Fig. 1 the pivot b and set-screw c, operating in the concentric slot, show how the direction of the drill-spindle may be changed, so as to enable the boring of the hole at any angle with relation to any object to which the apparatus may be affixed; and it is obvious that by suitable arrangement the length of the frame may be extended or contracted to suit the work to be performed.

The drill-spindle E in the form of apparatus shown in Figs. 1 and 2 slides through the gear G, which, by a screw-pin running in the groove h, communicates its rotary motion to the spindle E, as will be understood by reference particularly to Fig. 3.

In Fig. 1 the drill-frame A is represented to be attached to the narrow projection of a window-frame, F, to bore through which and the hanging stile S the chuck has to pass close to the outer wall, N, projecting from the window-frame. The hole is shown as already bored and the chuck provided with the countersink-bar P, which is passed through the hole and furnished with the cutter R. In this condition, if the pull M is pushed outward and the drill revolved in the proper direction, the countersink may be furnished to the depth required.

As shown in Figs. 1 and 2, the clamps B B

are represented to be adjusted apart by set-screws and a screw, *a*, within the stanchion *d*, to secure the clamp to the window-frame or other object.

5 In operating the form of apparatus shown in Figs. 1 and 2 the revolution of the driving-spindle will give the requisite rotary motion to the drill-spindle, and the gradual drawing forward of the pull *M* will insure the progressively forward movement of the drill-spindle.

10 The form of apparatus shown in Figs. 4 and 5 is provided with a sliding frame, *D*, to which the drill-spindle is properly secured, and with gears and crank for effecting the revolution of 15 said spindle. Power applied to the crank-shaft will give revolution to the drill-spindle, while the slide *D* is fed progressively forward by a cord, belt, or chain, *e*, operated by a wheel or crank, *F*, nearer the foot of the device than 20 the driving-shaft of the drill-spindle. The manner in which this progressively forward movement of the drill-spindle is accomplished in this embodiment of my invention will be clearly understood without a detailed description 25 thereof.

30 Figs. 6 and 7 show another method of feeding the drill which may be employed instead of that shown in Figs. 1 and 3. In these views Figs. 6 and 7, *J* indicates the threaded portion of the drill-spindle *E*, which meshes 35 into a nut, *K*, which is held in place by a screw-pin, *P*. The revolving drill-spindle feeds in the desired direction when the tooth *L* is allowed to catch into one of the notches *n* in the rim of the nut *K*.

35 Various other modifications of the drill-feeding, clamping, or adjusting means may be employed without changing the character of my invention, and the apparatus, though represented in the drawings as applied to boring wood, may be used with slight modifications for drilling other materials.

40 I specially design this apparatus for light work, and as a handy tool for such purposes 45 its parts will be made as light as may be consistent with proper strength; but it is not my purpose to restrict the use of this apparatus to any particular work, as its adaptability to heavy work is obvious.

50 Having thus described my invention, what

I claim, and desire to secure by Letters Patent, is—

1. A drilling-tool comprising a frame, having a hinged foot constructed to be adjustably secured near the object to be operated upon, 55 mechanism for imparting a progressively forward movement to the drill-point, and mechanism for imparting the requisite rotary motion thereto, substantially as and for the purpose set forth.

2. A drill embodying in its organization a frame whose foot can be adjustably secured near the object to be operated upon, and whose top portion can be adjusted to enable the drilling-tool to penetrate at an angle to the vertical 65 axis of the foot of the frame, gearing for imparting rotary motion to the drilling-tool, and drill-feed mechanism whereby said tool is progressively fed forward simultaneously with its rotation, substantially as set forth.

3. The frame *A*, whose foot-piece is provided with a clamping mechanism, one of the jaws, *B*, whereof is rigidly secured to said foot-piece, in combination with a drill-spindle, gearing for imparting rotary motion to said 75 spindle, and the pull *M*, connected to the top extension of the drill-spindle and extending down near the foot of the drill-frame, whereby a forward or backward movement may be imparted to the drilling-tool, substantially as set 80 forth.

4. The frame *A*, constructed to have one of its members adjusted at an angle with relation to its other member, and provided with adjustable clamps at its foot, in combination with the 85 drill-spindle, gearing to effect the rotary movement of said spindle, and the pull *M*, connected to the top extension of said spindle and extending down to near the foot of the drill-frame, whereby a progressively forward movement of the drill-spindle may be effected, substantially as set forth.

Signed at New York, in the county of New York and State of New York, this 16th day of May, A. D. 1885.

RUDOLPH D'HEUREUSE.
